HOT-SPRAYING METHOD AND APPARATUS

Wilhelm Kopperschmidt, Hamburg, Germany

Application April 27, 1950, Serial No. 158,447

9 Claims. (CL 299—58)

1

The present invention relates to a process for preparing, heating, melting and spraying lacquers, thermoplastics, metals, and other corrosion-resistant materials which have to be heated before application; and is generally characterized in that the heat required to melt or to change the viscosity of the spray medium is imparted to the latter in several steps at several zones.

The apparatus required to perform the present hot-spraying or coating method comprises generally a tightly closable pre-heating or melting vessel having a bottom screen with thereabove arranged heatable pipe coil or grating, a receptacle with a filter beneath said vessel, circulating and pressure-increasing means, a heatable pipe coil, a spray nozzle arrangement within the melting vessel, and heatable material feed hoses with attached heatable spray or coating devices.

For the application of meltable, thermoplastic, or liquid materials as spray mediums for corrosion-resistant, insulating or the like finishes or coatings, provides the present invention a method for melting or pre-heating material in a container or vessel; for additional heating of pre-heated or molten material within a receptacle beneath an interposed screen below the melting vessel; for continued heating of the liquid material within a heated pipe coil; and finally for hot-keeping or additional heating within the feed lines, consisting of pipe or hose, and in the spray gun or spray-medium applying device. Actual melting of materials, which are solid or paste-like at normal temperatures, takes place within a melting vessel and is effected by continuous overspraying and over-splashing of the solid lumps with already molten and hot material kept in circulation. Heating within the main heating zones and during the various steps of the melting and pre-heating process is effected by indirect heating. Cleaning and rinsing of vessel, receptacle, pipes, hoses and other devices used in the process, is performed with a cleaning fluid by applying the same circulating and control means as provided by this invention for the process itself, and with or without the assistance of pressure means such as compressed air, gases or the like.

Methods and processes previously introduced, generally apply direct heating methods within a crucible or the like by which relatively great temperature differences are created between the heat imparting surfaces and the material to be heated. Such concentrated heat causes uneven temperature distribution and overheats the material in spots which fact is reason for hardening,

2

carbonization, skin-formation and other troubles. On the other hand, is by such methods the heating period, nevertheless, relatively long. Furthermore, are apparatus and equipment hitherto constructed, complicated, have low efficiency, and are not fool-proof. They require considerable starting periods and cause difficulty during and after rest periods by chilled and congealed material contained in some parts of the apparatus, such as pipes, valves, spray devices, etc., which are not sufficiently heated.

The present invention has as its main object to overcome the disadvantages of present heaters constructed for the purpose in view and to provide an apparatus which is simpler in operation, reliable in service, high in efficiency and low in cost.

Another object of this invention is to increase the range of application of hot-spraying methods to include spray materials which, due to their inherent unfavorable properties, could not be applied heretofore because adequate spray equipment was not available.

Other objects and features of this invention will become apparent on hand of the following detailed description when taken in connection with the accompanying drawings which show diagrammatically some preferred embodiments of this invention and in which:

Fig. 1 shows a side elevation, partly in section, of a melting and heating apparatus for hot-spraying;

Fig. 2 shows a diagrammatical section of a spray device with double-hose connection for spray medium and a single-hose connection for heating medium;

Figs. 3 to 8 show various modifications of heatable double-hose and multiple-hose connections to suitable spray devices, whereby the hoses serve in various ways as feed and return lines for spray and heating mediums.

Referring now to Fig. 1, the heating apparatus here represented has a pre-heating vessel 1 with removable but tightly closable cover 2, a screen bottom 3 which may be plane, conical, or spherical up- or down-ward. The vessel 1 has an extension beneath screen bottom 3 forming a receptacle 4 with filter screen 5 into which material flows which has been molten and pre-heated in vessel 3. Receptacle 4 is in connection with a circulating and pressure-boosting pump, for example, a gear pump, through pipe line 6. Another pipe line 8 leads from pump 7 to a pipe coil 9, surrounding pre-heating vessel 1. At its other end connects pipe coil 9 to a line 10 with in-

serted shut-off valve 11 which terminates in a coupling or joint serving as connecting means for a feed hose of a spray device 12 (Fig. 2). A series of spray nozzles 13 are suitably distributed around the upper inside portion of vessel 1 from which jets of hot medium may be directed to impinge upon the solid or paste-like material deposited within said vessel. Nozzles 13 can be brought in operative connection either with a pipe line 14 which in turn joins the above mentioned feed line 10 through a shut-off valve 15; or, through a line 16 with inserted shut-off valve 17, to a line 18 terminating in a coupling or joint to which a return hose of spray device 12 (Fig. 2) is to be connected. Thus the spray nozzles 13 may be brought in connection either with the feed line 10 or with the return line 18 of the spray device for reason to be described later. Line 10, leading to pipe coil 9, may be operatively connected through line 19 with inserted shut-off valve 20 and line 6 to the receptacle 4 with filter 5. Connecting line 19 may be brought into operative connection with return line 18 of spray device 12 (Fig. 2) through line 21 with shut-off valve 22. A heating coil 23 is arranged within the bottom portion of vessel 1 in spaced relation to screen bottom 3 through which coil a heating medium such as hot oil, derived from pre-heater 30, or pre-heated spray medium, branched off from the spray medium pipes, or steam may be passed; or which may be heated electrically; and on which cold, solid or paste-like spray medium 24 is placed when the apparatus is charged. In this manner the charge is kept away from the screen bottom 3 and thus cannot clog the latter, but may be heated and molten readily when operation starts or when a new charge is introduced. Screen 3 may be plane or spherical toward top or bottom, as has already been mentioned, just as conditions make it desirable. A suitable heatable grating may also be used instead of heating coil 23. Basket-like screens or guards 25 are arranged around the inner side walls of vessel 1 which extend downward to the screen bottom 3, adjoining receptacle 4, to facilitate downward flow of material molten away from the solids 24, and at the same time permit heated spray mediums, which enter the vessel through nozzles 13, to circulate freely around said solids by action of circulating and pressure-boosting pump 7. Pre-heating and melting vessel 1 is surrounded by heat conducting material 26 such as graphite, aluminum chips, asbestos mixture, or other heat-conducting and heat-distributing material, into which electric heating elements 27 or steam or hot oil coils are embedded whose heating capacity may be regulated or adjusted by suitable switches or control devices. Vessel 1, receptacle 4 with filter 5, the circulating and pressure-boosting pump 7, and the connecting lines with shut-off valves and adjusting means are accommodated within a container 28 having heat-insulated walls. Within this container are also arranged one or more heating chambers 29 with suitable heating means 30 such as electric elements, steam coils, or coils for hot gases or hot liquids, as for example, glycerin, oil, etc. The heating chambers 29 are connected to measuring and control means 32, 33 and to a pressure gas or other heating source through a pipe line 31; to a circulating pump 79; and to a pipe line 34 with shut-off valve 35 leading to couplings or joints to be connected to hoses of spray device 12 (Fig. 2). A branch line leads from pipe line 34 to heating coil or grating 23.

In the embodiment of this invention as shown in Fig. 1 serves one heating chamber 29 by means of its heating fluid circulated by pump 79, to supply heat to heating coil 23 above screen bottom 3 and into the heated double-hose lines indicated in Figs. 2 to 8; and the other heating chamber 29, for the purpose of heating, a protective gas or a pressure gas to be used in the spray device 12 (Fig. 2) as will be described later.

Shut-off valves and control means as well as the circulating and boosting pump 7 are provided with heat preserving and heating means to shorten the starting period of the apparatus and to prevent that heated and therefore liquid material chills and congeals within these elements which otherwise would clog and cause trouble. In some cases it may be advisable to heat container 28 in which above elements are accommodated at times completely or partly, for which reason the drive motors of circulating and boosting pump 7 and circulating pump 79 have preferably to be shielded from the heat or be installed outside of container 28. The temperature within container 28 is preferably maintained within suitable limits by thermostatic regulators.

Some completely closed cleaning fluid reservoirs 36 and 37 and a pressure vessel 38 are mounted directly adjacent to container 28. Pressure vessel 38 is in connection with cleaning fluid reservoirs 36, 37 through lines 39, 40 with inserted shut-off valves 41, 42. Furthermore pressure vessel 38 has connection with intake line 6 of circulating and boosting pump 7 through line 43 with inserted check valve 44. Check valve 44 admits cleaning fluid into line 6 only under pressure and prevents return flow. Cleaning fluid reservoir 36 is in connection with shut-off valve 46 through line 45 and cleaning fluid reservoir 37 with shut-off valve 48 through a line 47. Both shut-off valves 46, 48 join with their opposite ends line 6 which in turn is in connection with circulating and boosting pump 7, as already mentioned above. Thus, the cleaning fluid reservoirs may be brought in operative connection with the pump at option. Pressure vessel 38 may be operatively connected to a compressed air source through a line 49 with inserted shut-off valve 50. Operative connection may also be established between pre-heating and melting vessel 1 and a compressed air or pressure gas source through line 51 with inserted three-way valve 52 and control and measuring instruments 53, 54. As has already been mentioned, can cover 2 of vessel 1 be pressure-tightly closed. The closing means 55 of cover 2 may be preferably interlocked with three-way valve 52 in such a manner that the cover cannot be lifted sooner than the operative connection with the compressed air or pressure gas source is interrupted and vessel 1, through three-way valve 52 and check valve 56, is vented to the open air or a pressure equalization vessel. Check valve 56, installed within vessel 1, prevents accidental entrance of hot spray medium or fuming particles thereof into line 51 at the moment of a sudden opening of three-way valve 52. A pressure-relief valve 82 in cover 2 prevents excessive pressures within vessel 1. The closing means 55 may be of the safety-type so they brake if sudden explosive pressures should develop within the vessel.

A gage 81, indicates the pressure of spray medium in line 10 leading toward spray device 12 (Fig. 2) which is the working or spraying pres-

sure. Thermo-couples or other temperature checking means are installed at various points along the circulating path of the heating medium as well as along the path of the hot spray medium, heating oil, and hot gases, to actuate temperature controls and quantity measuring instruments, and permit supervision of all phases of the melting process. A line 57 with inserted pressure relief valve 58 connects suction and pressure side of circulating pump 7 so that in case of excessive pressure within the spray medium circuit, pressure relief valve 58 opens and spray medium is by-passed. Thereby is the latter valve set for a suitable maximal pressure.

It will be understood that the apparatus with all accessories for universal application just described, may be simplified by omitting one or more of the accessories, if intended for use with only one certain spray medium, without departing from the scope of this invention.

Fig. 2 represents an embodiment of a spray device used in connection with the heating apparatus above described for spraying of spray mediums which are not solid when cold, by subjecting the latter to higher hydraulic self-pressure or by applying compressed hot gases to produce the spray. Spray device 12 comprises a spray chamber 59 with axially slideable nozzle needle 60 and nozzle 61. A heating chamber 62 for hot air or hot gases is arranged around the front portion of chamber 59 and the hot gases supplied under pressure to chamber 62 may, completely or in part, be applied to atomize the spray medium issuing from the nozzle or to form a protective gaseous jacket around the spray jet. Spray chamber 59 has connection with the heating apparatus (Fig. 1) through spray medium feed line 65 which is surrounded by a jacket hose 66 consisting of pressure- and heat-resisting material, such as certain rubber grades, and through whose jacket space 67 spray medium which has not been ejected through the nozzle, is returned to the heater. Another single hose or a double hose is connected to hose coupling 63 and serves to feed or to circulate hot compressed air or heated fluid from heating apparatus Fig. 1.

In the spray device according to Fig. 3 serves a hose 66 connected to coupling 69 as feed line for hot spray medium. Another inner hose 65 is accommodated within hose 66, joining the sprayer at 68, through which hot compressed air or gas is passed serving to heat spray chamber 59, or to atomize spray medium, or to form a protective jacket.

In the modification of a spray device shown in Fig. 4 serves the same double hose 65, 66 to supply hot spray medium and hot compressed air or gases to the sprayer, whereby hot spray medium passes through the inner hose 65 and the heating gases through the jacket space 67 between inner hose 65 and jacket hose 66.

In another modification shown in Fig. 5, it will be noted that besides the double hose 65, 66 similar to the one shown in Fig. 4 and joining at 68, 69, an additional single hose 70 is joined to the sprayer at 65. In this arrangement serves the inner hose 65 to feed spray medium and the jacket hose 66 in cooperation with single hose 70, serve for circulation of heating medium such as hot oil, hot air or the like. The circulating direction within single hose 70 and jacket hose 66 may be so chosen that either unidirectional or counter-directional flow of the two mediums, that is heating medium and spray medium, results in the double hose 65, 66.

The spray device shown in Fig. 6 has provisions for the connection of two double-hose lines 65, 66, whereby preferably the inner hoses 65 serve as feed and return line for hot spray medium and the outer or jacket hoses 66 for the passage of heating medium. Hereby also, either uni-directional or counter-directional flow of the mediums may be chosen depending on which method is most suitable for a certain application.

According to Fig. 7 is a suitable number of from two to four single-hose lines 65, 65, 72, 73 inserted into a protective jacket hose 71. One hose 65 serves as feed line for hot spray medium. When two hoses 65, as indicated in Fig. 7, are applied, serves one as feed and the other as return line for spray medium between heating apparatus Fig. 1 and spray device 12. Hose 72 serves in cooperation with jacket space 67 of jacket hose 71 for circulation of hot oil or hot gases for the purpose of heating spray medium within the line and in the spray device. A further hose 73 may be added to serve as supply line for hot compressed air or gas, used to improve atomization of the spray or to form a protective gas jacket around the spray. It has been found advisable to combine the hoses 65 into a double hose as shown in Fig. 4 several feet before joined to the sprayer, in order to enhance the movability of the setup.

A line system of three to five single hoses is packed in heat-insulating material 74 within a protective metal hose 75 in an arrangement indicated in Fig. 8. The single hoses serve as feed, or as feed and return lines, for hot spray medium and heating medium, and in addition for supply of compressed air or gases needed for atomization or spray jet protection. The single hoses preferably emerge from the protective hose 75 several feet before joined to the sprayer 12 and are at the same point combined into double hoses leading to the sprayer in the same manner as shown in Fig. 6.

The inner hoses according to Figs. 2 to 8 are preferably of the flexible metal-type, whereas the outer or jacket hoses, according to Figs. 2 to 7, consist of heat-insulating material such as artificial rubber, fabrics, or the like and are surrounded by a pressure-resisting covering. The jacket hose according to Fig. 8 needs only to confine and protect the insulating material 74 and may be accordingly constructed. For hot-spraying by self-pressure, according to the present invention, have the inner hoses to withstand temperatures of about 400 degrees centigrade and pressures up to 4000 lb. p. sq. in., depending on kind of medium applied.

The term thermoplastic materials as applied throughout the description of this invention is intended to include all such materials which, by increase of temperature, either change their viscosity or convert from a solid into a liquid state of varying viscosity. In applying material, such as bitumen, synthetics, or the like as spray medium for protective coatings against chemical deterioration or as insulation, with the apparatus of the present invention, the generally solid material lumps 24 are placed on heating coil or grating 23 in pre-heating vessel 1, cover 2 is tightly closed, and electric, steam, or fluid heating means 27 turned on to melt the material. The screens or guards 25 around the inner wall of the preheating vessel assure thereby free downward flow of molten spray medium through screen bottom 3 and into receptacle 4 which is also electrically, steam- or liquid-heated

and in which the temperature of the molten material is further raised. The spray medium then passes the filter screens 5 and enters line 6 leading toward circulating and pressure-boosting pump 7. The level of molten spray medium rises, reaches finally screen bottom 3 and comes in contact with still solid lumps on heating coil 23, and accelerates in coaction with the latter the melting process. The circulating and pressure-boosting pump 7 presses liquid spray medium through line 8 into pipe coil 9 wherein heating means 27 cause a further increase in temperature of the spray medium to a suitable working value which may be as high as 500 degrees centigrade and above. The melting process of solid or paste-like material within pre-heating vessel 1, can be further accelerated, after enough liquid material has accumulated within receptacle 4, by applying circulating pump 7 to pump spray medium, whose temperature has been raised to working temperature within pipe coil 9, into line 10 and adjoining line 14 to be issued through nozzles 13. Thus, hot material is splashed over the still solid lumps with the effect of greater heat penetration and faster melting. Having now sufficient working-hot spray medium within the apparatus, some of it may be diverted for spray application by opening shut-off valve 11 and admitting it through the adjoining hose coupling into feed lines 64, 65 of spray device 12 (Figs. 2 to 8). Spray nozzles 13 within pre-heating vessel 1 may be connected to the spray medium return line 18 by opening shut-off valve 17 in which case, however, the temperature of the spray medium issuing from the nozzles 13 is somewhat lower in account of losses within the hoses leading to and from the spray device 12. During continuous operation of the setup is steady melting of solid material, resting on heating coil or grating 23 within pre-heating vessel 1, preferably effected by spraying and oversplashing with hot material through nozzles 13. Thus, it is possible to begin spraying operation after a relatively short starting period and to melt-down practically only such quantities of spray medium as actually are used-up by spraying. This fact offers the advantage that relatively small and light equipment will suffice for substantial quantities of material to be dispersed, because the rate of melting-down depends to a great extent on the amount and temperature of liquid material ejected from nozzles 13 onto the solid material.

When applying only a spray medium feed line between heating apparatus Fig. 1 and spray device 12, shut-off valve 11 is opened and the pressure regulated with regulating valve 15 to a value, corresponding to an amount which can be consumed by spray device 12. Only a small portion of liquid spray medium is thereby diverted into the feed line, whereas the greater part is kept in circulation through line 14 and ejected through nozzles 13 by action of circulating and pressure-boosting pump 7. When material is worked with, which is not solid when cold, the circulating and ejecting action of pump 7 may be stopped by opening a shunt line through valve 80. Spray medium, pre-heated in vessel 1 may instead be pressed by compressed air or gas into pipe coil 9, to undergo further heating, up to reach working temperature, and hence, after opening of shut-off valve 11, directly into the feed line of the spray device. If material, which is not solid when cold, is to be sprayed under self-pressure, remains valve 80 closed and

circulating and pressure-boosting pump 7 presses material, emerging from receptacle 4, through pipe line 6 under high pressure into pipe coil 9 from where it enters through shut-off valve 11 into feed line 65 (Figs. 2 to 8) of spray device 12, and, when a return line is applied, returns through such line, reentering the heating apparatus through pipe line 18, after valve 22 has been opened, progressing to the inlet side of circulating pump 7 and, after having passed the same, is pumped into pipe coil 9 where it regains temperature and repeats the circulation thereafter as just described. It is advisable not to operate spray nozzles 13 when working with material which is not solid when cold and so heat only smaller amounts at a time which can be readily sprayed out within short periods. Spray medium fed into the spray device but not sprayed out returns through lines 67 or 65 to heating apparatus Fig. 1 and enters, after shut-off valve 17 has been opened, into line 14 leading toward nozzles 13 whereby supply to said nozzles through line 10 may be interrupted by closing shut-off valve 15. However, if it is desirable not to operate spray nozzles 13, such feed-back spray medium may also be deviated into lines 21, 19 and 6 toward the suction side of circulating and pressure-boosting pump 7 if shut-off valve 22 is opened.

Double or multiple hoses serve generally to pass hot spray medium between heating apparatus Fig. 1 and spray device 12 in such a manner that spray medium either flows in an inner hose, where it is protected against heat-dissipation by a surrounding jacket hose through which heating medium is circulated, or that the spray medium flows in the jacket hose and the heat dissipated is replenished by the heating medium flowing in the inner line. When two hoses 65 for feed and return of hot spray medium are applied, it has been found advisable to also construct the return line as a heatable double hose to prevent congelation of back-fed medium. Heating of the hoses may be accomplished by hot liquids or hot compressed gases such as compressed air, whereby a fraction of the circulating hot gases may be ejected from the spray around spray nozzle 61 to improve atomization of the spray or to form a protective gaseous jacket around the issuing jet. If spray mediums have to be applied which can stand the high temperatures necessary for their spraying only for very limited periods, a method applicable with a spray device according to Fig. 5 is used whereby the hot spray medium, when leaving pipe coil 9, has yet a safe temperature but has not attained its working temperature and on passing through hose 65 is subjected to the heating effect of heating medium with higher temperatures circulating in the surrounding jacket hose 66. Thereby is the circulating path of the heating medium, through jacket space 67 and single hose 70 either uni-directional or counter-directional with the spray medium to be further heated. Thus, the temperature-sensitive spray medium attains its proper spray temperature not sooner than shortly before it is ejected into the spray. Temperature and the rate of flow of the heating medium, which is circulated by pump 79, has to be closely adjusted and held to calculable values depending on the length of the hoses, the temperature rise to be effected, and the rate of flow of the spray medium. The above method is recommended, when a temperature-sensitive spray medium will stand the most

favorable hot-spray temperature, at which it also has the proper viscosity, for only very short periods without harmful effects. Besides hot liquids, also hot air or hot gases may be used for hose heating with good results. When applying hose heating means, it is always advisable to provide a feed and return line for heating mediums such as air, gas or liquids. The application of gaseous heating means in the apparatus of the present description, requires the connection of heating chamber 29 to a compressed air or pressure gas source and suitable control and measuring instruments. When compressed and heated air or the like is circulated for the purpose of hose heating, it gives the advantage that a fraction of it may simultaneously be used in the spray device proper to assist in atomization of the spray medium or, in hydraulic self-pressure spraying, to form a protective gaseous jacket around the issuing and dispersing spray jet. For very close temperature control of spray medium within the hoses, heating elements may be arranged around the latter, having automatic control by thermostats and being mechanically protected to the outside by a suitable covering.

Means are provided in the present apparatus to introduce certain gases into the spray medium by absorption under pressure. For this purpose vessel 1 can be operatively connected to a compressed air or pressure-gas source with control and measuring means 53, 54, through line 51, three-way valve 52 and a check valve 56. Gases entering this way into vessel 1 will be absorbed by the spray medium, issuing in a fine hot spray from nozzles 13, to an extent which depends on pressure and temperature within the vessel, and on the chemical condition of gases and spray medium. Such an intimate and perfect intermixture of gases may be advantageously applied in certain chemical transforming processes of the spray medium. Furthermore, tend the under pressure absorbed gases of certain chemical compounds to escape again under normal pressure. In the present process is spray medium, which has absorbed gases under pressure, released to normal pressures the moment it issues from the spray nozzle 61. The so escaping gases improve dispersion of the spray or may create a lather-like emulsion and spongy coatings sometimes desirable for insulation of surface or the like. If, however, the surface to be finished has to be smooth and glossy, it is advisable to work without air pressure within pre-heating vessel 1 to prevent the formation of air bubbles.

The subdivision of the heating process of the spray medium within the present apparatus into several steps and zones offers the advantage that only moderate temperature differences prevail between the spray medium to be heated and the contacting heat-imparting surfaces, whereby is assured that partial overheating is not encountered and troubles such as carbonization, gelatination, clogging, disintegration or the like are not likely to occur. Thus even extremely heat-sensitive spray mediums can be applied with perfect results. Arrangement of heater coil 23, pipe coil 9, and spray nozzles 13 in connection with circulating and pressure-boosting pump 7 allow by proper operation very short starting periods at the beginning and quick recuperation after subsequent new charges, and so assure uninterrupted service.

The heating apparatus with all accessories as just described, results in a relatively small and

light spray setup which may be moved without difficulty even to hard accessible places. The means for heating spray medium and keeping it hot within connecting lines of any length and within the spray device permits rest periods of any duration and hot-spraying of otherwise unaccessible surfaces such as within small rooms, inner walls of containers and boilers, structural steel works or the like. The chamber within container 28 which contains the pipe lines, shut-off valves, circulating and pressure-boosting means, is preferably filled with heat-conducting material such as graphite or the like having heating elements or heating coils embedded in it especially within the vicinity of above named units. By such means they may be heated independently and quickly during starting periods, to accelerate temperature rise and may be kept warm during rest periods to prevent spray medium, entering through line 6, from chilling and clogging the passages. Suitable measuring instruments are installed and connected to outlet line 10, in order that temperature and pressure of the spray medium on leaving the heating apparatus may be continuously controlled and registered, and the heating means within the apparatus correspondingly be adjusted. It is optional to perform these adjustments manually or automatically.

It will be understood that the present heating apparatus may be modified in construction and arrangements of parts and in application of means in various ways without departing from the scope of this invention. The apparatus is primarily devised for hot-spraying of thermoplastic materials, but may also well be used for materials which require less heating. In the latter case need the heating means to be adjusted only for moderate temperatures. Heating coil 23 can thereby be heated with hot spray medium by operatively connecting said coil in a suitable manner to the uppermost winding of pipe coil 9. If, however, a short starting period with quick temperature rise is essential, it is preferable to heat coil 23 with hot heating medium derived from heating chamber 29, or by steam or electricity.

Cleaning of the apparatus after it has been used for heating of thermoplastic material for some time or when changing from one spray medium to another, is, according to this invention, performed in an easy manner by flushing with cleaning fluid as will now be described:

After having sprayed out all remnants of spray medium from all pipes and fittings which will leave by normal operation and after having drained the remaining material from the lower parts of containers and pipe lines through drain valve 33, cleaning fluid from reservoir 36 or 37 is admitted to the system by opening one of the shut-off valves 41, 42. After a sufficient amount of cleaning fluid has entered, valve 41 or 42 is again closed and pressure gas admitted into pressure vessel 38 through line 49 by opening shut-off valve 50. Cleaning fluid is thereby pressed through line 43 and check valve 44 into pipe line 6 and, hence, into all containers, receptacles, pipe lines, valves and hoses. Manifold circulation of cleaning fluid is effected by corresponding manipulation of valves and control means.

Pre-heating vessel 1 is rendered pressureless by correspondingly setting three-way valve 52. The cleaning and flushing action is considerably enhanced by operation of circulating and pressure-boosting pump 7 which passes cleaning

11

fluid through all lines and control means of heating apparatus Fig. 1 as well as through the connecting hoses and spray device 12. Cleaning fluid entering under pressure through filter screen 5 and screen 3 from the bottom into pre-heater 1 removes residuals and rinses the screens thoroughly. After pressure vessel 38 has been emptied of cleaning fluid, compressed gas, admitted to the vessel as above mentioned, follows through line 43 and check valve 44 into line 6 and in turn from the bottom into pre-heater 1 where it agitates the cleaning fluid contained therein. Such agitation improves further the cleaning action on filter screen 5, receptacle 4, screen 3, heating coil 23 and pre-heating vessel 1. After sufficient action of the first charge of cleaning fluid valve 50 is closed, the position of three-way valve 52 changed, and a return-line valve 46 or 48 opened whereby the soiled cleaning fluid is returned to reservoir 36 or 37 by action of compressed gas entering pre-heater 1 through line 51. Most of the cleaning fluid contained in pipe lines and hoses is thus also returned. Remnants may be drained off at joints and suitably placed drain valves. The same flushing and cleaning procedure may be repeated by admitting another charge of cleaning fluid into the system, but now from the other one of the reservoirs 36, 37 which still contains clean fluid. Each filling of cleaning fluid may be repeatedly used either for first rinse or for finish rinse according to its impurity. All flushing operations are performed with all containers and openings to the outside closed, in order that no dangerous gases can escape into the work room. This fact prevents health injuring and explosive fumes which usually form when cleaning fluids, which mostly have explosive character, evaporate into the atmosphere. As evaporation of cleaning fluids usually take place already at relatively low temperatures, though their boiling points lie much higher, losses of cleaning fluid by evaporation are also prevented by flushing within a closed system. When the cleaning fluid has been substantially soiled and contains so much foreign matter that it is not suitable for further use, it may be drained from reservoirs 36, 37 and the latter be filled with clean material.

The application of several hose arrangements according to Figs. 2 to 8 makes the following spraying methods possible: The arrangements according to Figs. 2 to 4 are preferably applied when it is necessary to spray materials which are not solid in normal temperatures but have at the most a high viscosity, whereas the arrangements according to Figs. 5 to 8 serve best when working with spray mediums which are completely solid at normal temperatures. When working according to a pure self-pressure spraying method under hydraulic self-pressure of between 70 and 400 lb. p. sq. in., without any compressed air or gas addition to the spray whatsoever, are the hot air or gases fed into heating chamber 62 of spray device 12 solely applied for heating or for formation of a protective gaseous jacket around the spray jet.

In the spray device according to Fig. 3, the inner hose 65 may be applied to pass heated pressure gases, whereas within the surrounding jacket hose 66 heated spray medium is fed into spray device 12.

The manner in which the hot material feed hoses of Fig. 8 are applied, is especially suitable for hot-spraying of materials which have to be heated to a temperature of well above 160 degrees

12

centigrade to get in a suitable condition for spraying.

If electric hose heating is applied, the electric heating elements are preferably embedded within the thermo-insulating material 74 packed around all feed hoses within the protective jacket hose 75.

An arrangement according to Fig. 5 should be a most simple and suitable one for normal use when working with at present most customary hot-spray mediums having working temperatures up to about 200 degrees centigrade. When using very temperature-sensitive spray mediums, a suitable pre-calculated amount of heat, depending on length of hoses and temperature required, may thereby be imparted to the spray medium while the same passes through feed hose 65.

It will be understood that of the various hose arrangements shown, all may be alternately or interchangeably applied or other combination as described be used.

The spray medium may be dispersed either by application of only correspondingly high hydraulic self-pressure, with or without a gas or hot air protective jet jacket, or only with compressed air for atomization of the spray medium. It is, however, also possible to apply hydraulic self-pressure in combination with compressed air for ejection, dispersion and atomization of the spray. All spray mediums such as thermoplastic masses, lacquers, paints or other liquids may be hot-sprayed with the present equipment either by using all or some of the heating means and accessories. Hot air, hot gases, hot liquids or electricity may be applied as heating means for the double hose lines, and electric heat, steam heat or hot fluid heat for heating of the several heating zones and accessories of the heating apparatus Fig. 1.

It is to be understood that the invention herein described in connection with a preferred embodiment thereof, is susceptible of various modifications, of changes in arrangement and construction of parts, without departing from the principles, spirit and scope thereof and I do not wish to limit myself to a precise arrangement except as hereinafter claimed.

I claim:

1. In a melting and spraying apparatus for thermoplastic materials, a melting and pre-heating vessel; a screen-like bottom in said vessel; a grid for supporting said material in spaced relation above said bottom; a receptacle beneath said bottom; a pipe coil around said vessel; means for heating said grid, receptacle, and pipe coil; spray nozzles within said vessel; means effecting communication between said vessel, receptacle, pipe coil, and spray nozzles to form a closed system thereof; pressure inducing means in said system to effect circulation of the molten material; and means connecting said system with a point of use for said molten material.

2. An apparatus as set forth in claim 1, including a return conduit from said point of use for the return of unused material to said system.

3. An apparatus as set forth in claim 1, including heat conducting material in which said vessel, receptacle, and pipe coil are embedded, heating means embedded in said heat conducting material, and means for controlling the heat in said heating means.

4. An apparatus as specified in claim 1, including a basket-like screen within said vessel, located

at some distance inside the walls of the vessel and extending downwardly to said screen bottom.

5. An apparatus as specified in claim 1, in which said circulating and pressure-inducing means comprises a high-pressure pump.

6. An apparatus as in claim 1, including a container for cleaning fluid conduit means connecting said container with said circulation system, and regulating means for said conduit means.

7. An apparatus as in claim 1, including a pressure-gas source, conduit means connecting said source with the circulation system, and regulating means for said conduit means.

8. In a process of melting a thermoplastic material and maintaining it in a hot condition suitable for spraying, by application of heat through conduction and radiation thereto, the improvement comprising the steps of applying an additional amount of heat to the unmelted material by spraying said material with part of the melted and heated material in a closed vessel and introducing pressure gas in the melted material.

9. In a process of melting a thermoplastic material and maintaining it in a hot condition suitable for spraying, the steps comprising applying conductive and radiating heat to said material in a solid state in a closed vessel, conducting the material in a molten state from said vessel in a closed conduit system, applying additional heat

to the material in said system, conducting a part of said molten material back to the unmelted material and spraying it onto said unmelted material, conducting another part of said molten material from said system to a point of use during further application of heat and returning to said system any unused part of the molten material conducted to said point of use.

WILHELM KOPPERSCHMIDT.
